UNITED STATES PATENT OFFICE.

WILLIAM G. FUERTH, OF NEWARK, NEW JERSEY, ASSIGNOR TO EQUILIBRATOR COMPANY, OF NEWARK, NEW JERSEY, A CORPORATION OF NEW JERSEY.

STENCILING.

1,087,441.

Specification of Letters Patent.

Patented Feb. 17, 1914.

Application filed November 15, 1913. Serial No. 801,108.

To all whom it may concern:

Be it known that I, WILLIAM G. FUERTH, a citizen of the United States, residing in Newark, in the county of Essex and State of New Jersey, have invented certain new and useful Improvements in Stenciling, of which the following is a specification.

This invention relates to stencil sheets, such as are formed by coating Yoshino paper with glue or gummy substance which is rendered impervious by means of an astringent or fixing agent. Sheets of this character are disclosed in the British patents to De Zuccato, 12,136 of 1894, and 18,851 of 1893. In making a stencil from these sheets coated with glue or gelatin, it is customary to soften the coating by an application of water or other suitable emollient. In consequence, the rolls and other portions of the typewriter are apt to become gummy by reason of contact with the softened coating on the sheet. It is also found in making such stencils that the lines cut by the types are objectionably fine, this being due to the fact that the types in the typewriter are of the "hair line" variety, having sharp edges, which make very thin indentations in the gum on the stencil sheet. Stencil sheets of this character are dyed a dark color, and when writing a stencil it is provided with a light colored backing, so that the operator can read the stencil as work thereon progresses in the typewriting machine.

One of the objects of the present invention is to avoid the difficulty before mentioned, of gumming up of the typewriter rolls and parts by the moistened coating of the stencil sheet, and also to strengthen the characters which are formed or cut in the stencil, so that more legible and desirable inked copies may be made therefrom, and also to accomplish these results without sacrificing the advantage of having the characters written on the stencil sheet legible as the writing thereon progresses in the writing machine. These objects are accomplished by means of the device shown in the accompanying drawing, in which A is the backing sheet; B is a stencil sheet coated with glue or other gummy substance which is rendered impermeable and which is also moistened preparatory to cutting the stencil thereon in the typewriting machine; and C is a facing of oil tissue paper which overlies the moistened stencil sheet; said sheets being

preferably attached together at their leading edges above the line D. The overlying sheet C does not become dampened from the water or emollient with which the stencil sheet B is treated, because said overlying sheet C is oiled to prevent it from absorbing moisture, and it serves to prevent either the rolls or any other part of the typewriter from contacting with the water or emollient or softened gum. Moreover, the sheet C performs the function of enlarging the cuts made by the types in the stencil sheet B, so that the inked copies will more nearly resemble ordinary inked ribbon type impressions. In other words, this sheet C serves to make wider orifices or apertures in the gummy coating, through which orifices the ink is transmitted in the subsequent printing process. The impact of the type face, is, by means of the intervention of the overlying sheet C, distributed over a somewhat larger area than such impact would effect upon the unprotected sheet. Any given line of type coming in contact first, with the overlying sheet C, carries such sheet with it against the coated sheet and thus knocks off the coating through a rather broader line. In other words, the outside sheet distributes the effect of the blow somewhat. The effect is the same as if type, blunter on the edge than the usual sharp edged type, were used. This not only makes better inked copies, but also avoids another difficulty heretofore experienced, owing to the fineness of the apertures in the stencil sheet, which is the liability of the openings in the stencil being closed at many points by reason of the pressure to which the stencil sheet is repeatedly subjected in the stenciling machine during the printing process. When the stencils are made by the use of this sheet C, the openings made are so wide that there is no liability of their becoming closed. This is an important feature in this class of stencils which are sometimes capable of making many thousands of copies, so that there is ample opportunity for a narrowly-cut stencil to be closed before the run of thousands of copies is completed.

The stencil sheet B is dyed, preferably a dark color, and the backing A is preferably a light color so that the type impressions made on the stencil sheet may be legible to the operator as he proceeds to make them in the typewriting machine, and this legi-

bility is preserved to a satisfactory extent when the overlying sheet C is employed, because such sheet C is transpicuous, the oil serving to increase this quality of the sheet C. The typewritten words on the drawing indicate the stencil B partly made or cut out, and are visible through sheet C. It will be understood, however, that many of the advantages of the invention may be gained without oiling the overlying sheet C.

After moistening the stencil sheet B with the emollient, the surplus moisture is blotted off, and the sheet C, either oiled or not, is laid down upon the sheet B, and the whole inserted in the typewriting machine. As is well known in operating typewriters, the work-sheet drags over the top edge of the usual paper shelf, and it has been found heretofore in using the dampened glue-coated stencil sheets in the typewriting machine, that said top edge of the paper shelf accumulates gum from the stencil sheets, and as a result the work-sheet is apt to adhere to the paper shelf in a manner to cause the work-sheet to feed askew in passing between the feed rolls of the typewriter. Moreover, the little soft rubber feed rolls which usually press the work-sheet against the platen of the typewriter, by reason of repeatedly running upon the softened glue of the stencil sheet, have been found to become coated or smeared with the glue composition, with very objectionable results, especially when using the machine in the ordinary way for inked type impressions after making a lot of stencils upon the machine. These disadvantages are all overcome by the present invention, and moreover, the types do not take off any glue from the coated sheet, and by coöperation with the cover sheet, make an important improvement in the impressions in the stencil sheet, as already explained.

Another advantage flowing from my invention is in the attaching together of the sheet A, B and C. It will be seen in the drawings that a metal hammer or jaw E, which is heated, presses the three sheets upon an opposing anvil or jaw F. The heat of the jaw E softens the glue in the sheet B and therefore causes it to unite firmly to the sheets A and C. The sheet C prevents the softened glue from sticking to the jaw E when the latter is raised. Thus the expense of attaching the sheets together is reduced to a negligible point. In fact, the three sheets can be fastened together in this manner at such a low cost that the expense of producing the three-sheet structure may be the same as, or even less than, the expense of producing a structure consisting only of the sheets A and B, owing to the difficulty of attaching A and B together at their top edges, the heated jaw hammer or vise not being available when the two-sheet

form alluded to above is used, owing to the difficulty that the glue would stick to the hammer or jaw E. Thus it will be seen that by this invention the cost of the ultimate structure is reduced, it contains more parts, and has the important advantages already explained. As to some of these features, however, the invention is not limited to three sheets secured together in the manner described.

It will be seen that in connection with a membranous coated stencil sheet such as Yosho paper having a glutinous or gelatin coating, the glutinous or gelatin solution being usually glycerinated, so that the stencil sheet B is impervious and requires moisture to modify the same for stencil purposes, said sheet being preferably mounted on an impervious backing sheet A, I have provided a porous or tissue front sheet to insure certainty in cutting the stencil, and especially valuable in protecting the sheet-feeding devices of the typewriting mechanism from being smeared with moisture oozing from the stencil sheet, thereby preventing the gumming or clogging of the typewriter carriage and the soiling of the work-sheets used in ordinary correspondence and other typewriting, after the typewriting machine has been used for cutting a moist stencil. If desired, this cover sheet C may be retained upon the stencil sheet B during the printing process, although this is not necessary. If retained, it serves as a protector which receives much of the wear and tear of the stenciling machine and tends to prolong the life of the stencil itself. This sheet is thin and open enough in texture to permit the ready passage of the ink. Moreover, at the places where it has been struck by the type its texture has been injured or broken down to such an extent as to render the passage of the ink still more easy.

It is very often desired to fill out a stencil according to a certain form or arrangement of columns and wording, and to facilitate this, the form may be printed on the cover sheet C, as indicated at G, such printing being, of course, done by means of an ordinary printing press.

Variations may be resorted to within the scope of the invention, and portions of the improvements may be used without others.

Having thus described my invention, I claim:

1. A collation of sheets for typewriter stencil purposes, comprising a coated stencil sheet adapted to be moistened preparatory to being typewritten, and having a backing sheet covered with a moisture resistant tissue sheet to prevent the moisture from the dampened stencil from oozing out onto the parts of the typewriting machine.

2. A collation of sheets for typewriter

- stencil purposes, comprising a coated stencil sheet adapted to be moistened preparatory to being typewritten, and having a backing and covered with a tissue sheet to prevent the moisture from the dampened stencil from oozing out onto the parts of the typewriting machine, said tissue sheet being oiled. 5
3. A collation of sheets for typewriter stencil purposes, comprising a stencil sheet having an impervious coating which must be moistened preparatory to having a stencil typewritten thereon, a backing for said stencil, said backing and said stencil being 10 of contrasting colors so that the stencil may be legible as the writing thereof progresses, and a transpicuous overlying sheet through which the writing on the stencil is still legible, to protect the typewriter parts from 15 being smeared with moisture or gummy substance from the stencil, and to widen the apertures made in the stencil, substantially as set forth. 20
4. A collation of sheets for typewriter stencil purposes, comprising a stencil sheet having an impervious coating which must be moistened preparatory to having a stencil typewritten thereon, a backing for said stencil, said backing and said stencil being 25 of contrasting colors so that the stencil may be legible as the writing thereof progresses, and a transpicuous overlying sheet through which the writing on the stencil is still legible, to protect the typewriter parts from 30
- being smeared with moisture or gummy substance from the stencil, and to widen the apertures made in the stencil, said overlying sheet being an oiled tissue sheet to prevent the moisture from the dampened stencil from oozing out onto the parts of the typewriting machine, said tissue sheet having a form printed thereon. 35
5. A collation of sheets for typewriter stencil purposes, comprising a coated stencil sheet adapted to be moistened preparatory to being typewritten, and having a backing and covered with a tissue sheet to prevent the moisture from the dampened stencil 40 from oozing out onto the parts of the typewriting machine, said tissue sheet having a form printed thereon. 45
6. A collation of sheets for typewriter stencil purposes, comprising a stencil sheet having an impervious coating which must be moistened preparatory to having a stencil typewritten thereon, a backing for said stencil, said backing and said stencil being 50 of contrasting colors so that the stencil may be legible as the writing thereof progresses, and a transpicuous overlying sheet through which the writing on the stencil is still legible, to protect the typewriter parts from 55 being smeared with moisture or gummy substance from the stencil, and to widen the apertures made in the stencil, said overlying sheet being an oiled tissue sheet and having a form printed thereon. 60
